**COMBINATION FISHING ROD AND
LINE HOLDER**Robert H. Bojanowski, 14380 Knolson,
Livonia, Mich. 48150

Filed Jan. 28, 1974, Ser. No. 436,912

Term of patent 14 years

Int. Cl. D22—05

U.S. Cl. D22—25

Fig-1Fig-2Fig-3Fig-4

FIG. 1 is a perspective view illustrating a combination fishing rod and line holder showing my new design;

FIG. 2 is a side elevational view thereof and which view is identical to all other side views of the fishing rod and line holder;

FIG. 3 is a left-end elevational view thereof; and

FIG. 4 is a right-end elevational view thereof.

I claim:

The ornamental design for a combination fishing rod and line holder, as shown and described.
